UNITED STATES PATENT OFFICE.

FRANK BRIDGES, OF HARROW, HENRY FIRMAN, OF HARROW WEALD, HAROLD WILLIAM TISDALE, OF NORTH WEMBLEY, AND BEN DEAN WARD HOSKINS, OF WEALDSTONE, ENGLAND, ASSIGNEES TO WILLIAM RICHARD CODLING, OF LONDON, ENGLAND.

PRINTING MACHINE.

Application filed February 4, 1926, Serial No. 85,980, and in Great Britain February 5, 1925.

This invention relates to printing machines and has for its object to provide a machine for automatically printing inscriptions on the cut and aligned edges of books or blocks fed to it in continuous succession.

According to the preferred form of the invention, the books or blocks are passed through the machine in two movements more or less at right angles to each other, the edge opposite the bound edges being printed during one movement and one or both of the other edges being printed during the other movement. In the preferred form the machine includes two runways arranged at right angles, and the book is carried between guides through the first runway underneath a printing roller during which movement it stands on its bound edges. After receiving the impression, the book, still standing vertically is caught by a rotating arm which lays it flat on one cover in line with a second runway through which it is carried horizontally between two printing rollers rotating about vertical spindles which print the upper and lower edges. During both printings the edges are suitably pressed together to make a firm face for receiving the impression.

The invention is illustrated in the accompanying drawings in which:

Fig. 1 is an elevation,

Fig. 2 a plan, and

Fig. 3 is a view of a detail.

Fig. 4 is a broken view in elevation showing the spring means for controlling one of the printing rollers.

Fig. 5 is a plan view showing the spring means for controlling the pressure rollers.

Fig. 6 is an end elevation of the same.

Referring now to the drawing, the machine comprises a frame or frames 1, 2 arranged more or less L-shaped in plan and having a power shaft 3. The shaft 3 drives a shaft 4 carrying a bevel wheel 5 meshing with a second bevel wheel 6 on a shaft 7 and is adapted to be driven from any suitable source of power. The shaft 7 conveniently carries a chain wheel 8 connected by an endless chain 9 to a second wheel 10 mounted on a shaft 11. A second pair of wheels 12, 13 connected by a second endless chain 14 are mounted on the shafts 7, 11, the chains being united by spaced propelling-rods 15 set apart by a distance which is conveniently

greater than the height of the book cover. 55 Parallel guides 16, 17 are arranged above the spacing rods to provide a slot or guideway 18 through which the books are passed, the slot becoming slightly narrower in the direction of travel of the books and its width at 60 the narrow end being adjustable. A flat board or bottom 18^a is provided for the book to slide on during its passage through the slot. Preferably the parallel guides 16, 17 may be formed of vertical strips of sheet 65 metal to provide smooth surfaces capable of adjustment. Above the narrow end of the slot 18 is mounted a printing roller 19 working in conjunction with an ink-spreading roller 20 adapted to receive ink from a receptacle 21 through the intermediary of a third roller 22, the rollers and the receptacle being carried in a frame carried by one or more hinged arms 23 hinged about the axis of the shaft 7. The position of the printing 70 roller 19 is determined by one or more set screws 24 mounted in fixed arms 25 secured to the frame of the machine against which the hinged frame abuts under gravity, and the printing roller is driven through a train 75 of gears 26 from a gear wheel mounted on the shaft 7. A second pair of endless chains 29, 30 carried by sprockets mounted on parallel shafts 4, 27 is arranged at the end of the runway 18 and work in a direction at 80 right angles to the line of the said runway beneath a second runway comprising spaced boards 28. At or about the region at which a book fed through the slot 18 will traverse the line of movement of these chains, we provide a pusher arm 31 mounted on a continuously rotating shaft 32 adapted as a book is fed forward after receiving the first impression from the roller 19 to lay it down on to the second runway, a fixed rod 33 being set 85 up in line with the remote side of the slot to prevent the book falling the reverse way. The endless chains carry pairs of upstanding push-rods 34 spaced from each other a distance conveniently greater than the width of 90 the book, and these then carry the book forward between two printing rollers 35, 36 rotating about vertical spindles at each side of the runway. Before reaching the printing rollers, the book passes under one or more 95 trip levers 37 mounted on a shaft 38 carrying a contact electrically connected to the driving mechanism in such a way that if the 100 105

pages of the book are not flat, the shaft is rocked so as to break the contact so that the machine is stopped. The shaft carries a pair of spring-controlled arms 39 carrying rollers 40 which engage on the top of the book and press it down so that the edges form a solid face to receive the impression. A spring *c* encircles the shaft 38, being terminally connected to one of the arms 39 and 10 to the frame to insure operating pressure of the rollers 40. At the end of the runway 28 is provided a plurality of endless belts 41 in line therewith running at high speed so that the book is caught by the said belts and carried away from the runway quickly before the rods 34 are rocked below the runway for their reverse movement. A rocking arm 42 is also positioned above the slot 18 electrically connected to the driving mechanism 15 so that if a book is fed into the slot the wrong way up, the movement of the machine is stopped owing to the arm being raised by the additional height of the book so as to break a contact.

25 The type face on the printing rollers is carried by a raised portion 43 shown separately in Fig. 3 so that the rollers are adapted to permit the passage at each side of the type of boards or other backing which 30 may have slightly larger height and depth than the pages on which the impression is made. Preferably, the type is cut in a rubber strip 50 vulcanized on a leather band 51 carried round a roller of suitable size and 35 firmly secured thereto by means of plates 52, 53 secured by screws to the oblique walls of a recess in the face of the roller. By this means the printing roller can readily be set up, if necessary with a certain amount of 40 packing beneath the leather band, so that the operative length of the type face is equal to the distance between the propelling rods 15 or push rods 34 as is obviously necessary for repetition work, the gears being so 45 designed that in these circumstances the type face will move with the peripheral speed equal to the speed of the rods 15 on chains 9. The left hand frame carrying the vertical inking roller and ink supply therefor is fixed, 50 but the right hand frame 44 in Fig. 2 is hingedly mounted about a vertical pivot 45 and is spring-controlled and adjustable similarly to the horizontal inking roller, so that the machine can be set up on books of varying size. A spring *E* is connected to the 55 right hand frame 44 and passes beneath the sections of the table 28 and secured to a pin mounted on a transverse rail provides the spring control of the roller 36. The drive 60 is transmitted to the right hand roller through an idle gear wheel mounted at the joint of hinged links 46, 47.

With the construction of horizontal guides and vertical rods moving the book over fixed surfaces, the guides engaging the book when

vertical and the rods when flat, the timing of the movement of the book can be definitely set to agree with the rotation of the rollers so that the impression will be made at the right place along the edges of the book. Obviously if it is desired to operate only the first printing mechanism we can arrange to feed two or more books arranged side by side simultaneously through the machine.

It will be clear that owing to the pressure effected by the narrowed walls of the slot 18 on the one hand, and that effected by the rollers 40 on the other hand the cut edges of the book are held tightly to form a solid face to receive the impression, and that the means exerting the pressure is in both cases adjustable to books of different thicknesses.

Obviously by providing more than one roller for each run two or more colours can be printed during one passage of a book through the machine.

We claim:—

1. In a printing machine, a printing roller, means to feed a book past said roller with an edge directed thereto, means to cause said roller to print an impression on said edge during said movement, and means relatively to which the book is slidable to press the edges of the book together during said movement.

2. In a printing machine, a runway, means to feed a book through said runway, said runway directly engaging the book and supporting the same in an upright position, means to print an impression on an edge of said book during its passage through said runway, and means to press the leaves of said book together during said printing operation.

3. In a printing machine, oppositely placed guides, a printing roller arranged transversely of said guides, means to feed a book between and relative to said guides and means to print an impression on an edge of said book during its passage therebetween, and means whereby said guides press the leaves of said book together during said printing operation with sufficient force to present the edges of the leaves as a good printing surface.

4. In a printing machine, oppositely placed guides, a printing roller arranged transversely of said guides, means to feed a book between and relative to said guides, means to print an impression on an edge of said book during its passage therebetween, and said guides being adjustable to exert pressure on the faces of said book to press the leaves of the book together with sufficient force to cause the edges to form a good printing surface during said printing operation.

5. In a printing machine, oppositely placed vertical guides, a supporting surface therebetween, a printing roller arranged hor-

izontally above said guides, means to slide a book on an edge over said surface between said guides, and means to print an impression on an edge of said book during said movement, and means whereby said guides press the leaves of said book together during said printing operation.

6. In a printing machine, a printing roller having its axis vertical, means to feed a book lying flatwise past said roller to receive a printing impression on the edge of the leaves of the book from said roller, and means operating on the upper surface of the book as the latter passes said roller to cause the edges of the leaves to form a good printing surface during the cooperation of the printing roller with said leaves.

7. In a printing machine, a printing roller having its axis vertical, means to feed a book lying flatwise past said roller to receive a printing impression on the edge of the leaves of the book from said roller, and spring pressed rollers operating on the upper surface of the book as the latter passes said printing roller to cause the edges of the leaves to form a good printing surface during the cooperation of the printing roller with said leaves.

8. In a printing machine, a runway, means to feed a book standing on an edge through said runway, a second runway, means to feed a book flatwise through said second runway, means to print an impression on an edge of a book during its passage through each runway.

9. In a printing machine, a runway, means to feed a book standing on an edge through said runway, a second runway, means to feed a book flatwise through said second runway, means to print an impression on an edge of a book during its passage through each runway, and automatic means to transfer a book delivered at the end of the first runway to the feeding means for the second runway.

10. In a printing machine, a pair of vertical guides, a horizontal printing roller above said guides, means to feed a book standing on an edge between said guides, means to print an impression on an edge of said book during said passage, book-feeding means at the delivery end of said guides, means to lay over on one of its faces a book reaching the delivery end of said guides, and to engage it with said book-feeding means positioned there, and means to print an impression on another edge of said book during its conveyance by said book-feeding means.

60 11. In a printing machine, means for feeding a plurality of books therethrough in succession, a printing roller adapted to print an impression on an edge of a book during said feeding movement, means to adjust the setting of said roller to accommodate books

of different sizes, and guiding means for the book and relative to which the book is movable during the printing operation, said guiding means acting to compress the leaves of the book to cause their edges to form an effective printing surface.

12. In a printing machine, a runway, means to feed a plurality of books flatwise through said runway in succession, a vertically arranged printing roller at a side of said runway, a second oppositely placed vertically arranged printing roller at the other side of said runway, means to cause said printing rollers to print impressions on opposite edges of a book during its conveyance by said feeding means between said rollers, and means to press the leaves of said book together during said printing operation.

13. In a printing machine, a runway comprising vertical guides arranged at each side of a flat supporting surface, book feeding means comprising spaced members moved over the top of said surface, a horizontally arranged printing roller arranged above said guides, means to adjust the height of said roller above said surface, said guides being adapted to engage both faces of a book passed therebetween, a second runway arranged at an angle to said first runway and having a slotted supporting surface, means to lay flatwise on said second runway a book delivered vertically from said first runway, oppositely arranged printing rollers at each side of said second runway, means to convey said book between said rollers comprising a plurality of upstanding members moved simultaneously through said slots, and means to adjust the distance between said rollers to allow the passage of a book therebetween.

14. In a printing machine, a runway, means to feed a book therethrough, means to print an impression on an edge of the leaves of said book during its passage therethrough, means to exert a pressure on the book to maintain the leaves thereof in position to receive a printing impression, a second runway, means to feed a book therethrough, automatic means transferring a book from the end of the first runway to the feeding means of the second runway, means to print an impression on another edge of the leaves of the book during its passage through said second runway, and means in the second runway for exerting pressure upon the book during the printing operation to hold the leaves of the book in position to provide a good printing surface.

15. In a printing machine, a runway, a second runway, means to feed a plurality of books in succession through the first runway, automatic means to deliver a book from the end of the first runway to the second runway, means to print an edge of the

leaves of a book during its passage through the first runway, and means to hold the leaves of the book in compact relation to afford a good printing surface during the printing operation in the first runway, means to print another edge of the leaves of the book at right angles to the first edge during its passage through the second runway, and means to hold the leaves of the book in compact relation to afford a good printing surface during the printing operation in the second runway.

16. In a printing machine, book feeding

means comprising a pair of endless flexible members carrying book propelling means, and book withdrawing means comprising endless flexible members moving at a higher rate of speed than said first-mentioned members.

In testimony whereof we affix our signatures:
